UNITED STATES PATENT OFFICE

JEROME J. AULL, OF CINCINNATI, OHIO, ASSIGNOR TO THE LUNKENHEIMER COMPANY,
OF CINCINNATI, OHIO, A CORPORATION OF OHIO

WICK OILER

Application filed January 6, 1930. Serial No. 418,875.

My invention relates to wick oilers. It is the object of my invention to provide a wick oiler in which the rate of oiling on the delivery of oil to the wick will be constant so that the lubrication by the oiler will be at a uniform rate.

It is a further object to provide an oiler in which the level of the oil will be readily visible to an observer without disturbing the operation of the oiler.

It is a further object to provide a construction which is easily filled and cleaned, a great simplicity of construction and adequate strength to fulfill the demands made upon it.

Referring to the drawings:—

Figure 1 is a side elevation of my invention;

Figure 2 is a section on the line 2—2 of Figure 1;

Figure 3 is a section on a plane at right angles to Figure 2.

Referring to the drawings in detail, 1 is a stem of the oiler having a passageway 2 therethrough controlled by the valve member 3 which is provided with the usual handle 4 and a spring 5 for keeping the tapered valve member 3 in adjusted position. The passageway 6 of the valve member when registering with the passageway 2 permits the flow of oil from the enlarged passageway 7 that contains the wick 8.

Within the passageway 7 is a tubular member 9 which projects upwardly through the stem 1 into the interior of the oil cup. It acts as a support for the wick 8, the free end of which at 10 rests on the floor 11 of the cup having side walls 12 and a floor 11. This wick is held in position by a wire, one end of which is formed into a loop 13 for holding the wick 8 in its lowermost position within the passageway 7. The wire then extends upwardly, as at 14, and is bent over, as at 15, over the edge of the sleeve 9.

The lubricant is maintained at the level

designated 16 in the following manner. An inverted glass reservoir 17 is provided with a downwardly extending spout 18 and the level of the oil is located at 16 so as to cover the mouth of the spout 18. The liquid within the transparent container 17 is indicated at 19.

The glass reservoir is detachably mounted upon the cupped walls 12 by having its shoulder 20 resting upon the upper shoulder 55 or rim of the walls 12. It is retained in such position by the spring bail which is pivoted at 21 in the side walls 12 of the cup and is provided with spring loops 22 and a cross member 23 having a dipped portion 24 for positioning the vertically disposed latch member 25 that is yieldingly pressed on top of the glass reservoir 17 to hold it in position on the cup.

Thus it will be observed that as the lubricant 19 descends due to its being used through the wick 8 the level of the lubricant is always maintained at the level 16 and thus a constant supply under constant pressure is supplied to the wick with resulting 70 constant speed an amount of lubricant being delivered to the part to be lubricated.

Heretofore where the wick rested in a cup of lubricant as the lubricant descended the wick drew less and less oil from the 75 supply as the height of the supply diminished. This brought about an irregular lubrication.

Again, it is impossible to see the amount 80 of lubricant in the wick oiler without opening the oiler or providing expensive glass walls of heavy construction. This led to difficulty in cleaning because of deposit by the lubricant on the walls of the glass chamber.

In the present instance the replenishment 85 of the glass reservoir permits of the freest cleaning and adjustment of the wick oiler with consequent improvement in the effi- 90

ciency of the apparatus while at the same time providing for ready observation through the glass reservoir of the height of the lubricant.

5 It will be understood that I desire to comprehend within my invention such modifications as may be clearly embraced within the scope of my claims and invention.

Having thus fully described my invention, 10 what I claim as new and desire to secure by Letters Patent, is:

1. In combination, a cup, a stem leading from the cup to the part to be lubricated, means on said stem extending above the bottom of the cup, a wick located in the bottom of the cup and extending over and into said means extending above the stem and the bottom of the cup, an inverted reservoir resting on and forming a closure for said 15 cup and closed save for an open spout which communicates with said cup at a point below the top of the means extending into the cup above the stem and a spring bail for detachably locking said reservoir on said 20 cup.

2. In combination, an open top cup, a stem leading from the bottom of the cup, a sleeve in said stem extending above the cup bottom, a wick in the cup extending over and into 25 the said sleeve a closed inverted reservoir having a depending open spout mounted on said cup to close it, said spout being located to one side of said sleeve, a wick holder mounted on said sleeve and extending into 30 it comprising a hook for engaging the sleeve, a wick-engaging means and a detachable spring bail mounted on said cup engaging the bottom of said reservoir.

3. In a wick oiler, an open end cup, an 35 inverted reservoir having a shoulder engaging the upper edge of said cup, a depending spout from said reservoir extending into said cup, a tubular member mounted on the bottom of said cup extending above 40 the open end of said spout to one side thereof, means maintaining a wick in said cup and tubular member, a spring bail pivotally mounted on said cup extending around and over said reservoir and a depending locking 45 member mounted on said bail between it and the bottom of said reservoir.

4. In a wick oiler, an open end cup, an inverted reservoir having a shoulder engaging the upper edge of said cup, a depending spout from said reservoir extending into 50 said cup, a tubular member mounted on the bottom of said cup extending above the open end of said spout to one side thereof, means maintaining a wick in said cup and tubular member, a spring bail pivotally mounted on said cup extending around and over said reservoir, a depending locking member mounted on said bail between it and the bottom 55 of said reservoir and means of control

to prevent excess fluid through said tubular member on the wick through the bottom of the cup to a point to be lubricated.

In testimony whereof, I affix my signature.

JEROME J. AULL.
